UNITED STATES PATENT OFFICE.

THOMAS RICHARDSON AND MALCOLM MCINNES, OF FERGUS, CANADA.

IMPROVEMENT IN GANG-PLOWS.

Specification forming part of Letters Patent No. 177,078, dated May 9, 1876; application filed March 13, 1876.

To all whom it may concern:

Be it known that we, THOMAS RICHARDSON, manufacturer, and MALCOLM MCINNES, blacksmith, of the village of Fergus, in the county of Wellington, Province of Ontario, Canada, have invented Improvements in Gang-Plows, of which the following is a specification:

The object of our invention is to provide a light and strong gang-plow, in which the depth of the furrow can be easily regulated, and consists of four wrought-iron plates, shaped and bolted together, as hereafter specified, and provided with handles of the usual shape; also, the application of a hand-lever and quadrant, connected to and operating by means of rods and levers the wheels of the plow, as hereafter specified.

Figure I is an elevation. Fig. II is a plan. Fig. III is a detail of plow.

A is the center rail of the frame, bent at its back end, as shown, so as to meet the side rail B, to which it is bolted by the two bolts C and D. The flat neck of the back plow E fits in between these two plates or rails, and is held therein by the two bolts C and D. The other plows F and G have similar flat necks, and are likewise placed and held by the bolts H H and I I, which, respectively, hold the rails A and J to the brace K, as shown. L is the front axle, passing through the rails J and A, and cranked, as shown, the wheel L' being pivoted upon the short arm of the crank, as shown. The hind wheel M is attached in a similar manner to the frame, its axle M' being the same shape as L, but passing through the rails B and A. N is a hand-lever, the bottom end of which is fastened to the axle M'. O is a notched quadrant, bolted to the center rails A. P is a bell-crank, pivoted, as shown, to the quadrant O. Q is a rod, connecting the lever N to the bell-crank P. R is the rod connecting the said bell-crank to the crank S, which is fastened to the axle L, as shown. The holes

marked *r* in the bell-crank P are for the purpose of shortening the connection between the said bell-crank and crank S. T is the draft-plate, bolted to and forming a bridge between the rails A and J, as shown. V V are the handles of the plow, bolted and stayed to the frame of the gang-plow, as shown. Owing to the connection described between the hand-lever N and cranked axles L and M', any motion of the former correspondingly affects the position of the latter; but the relative position to each other of the wheels L' and M depends upon the position of the hand-lever N, and in which of the holes *r* the end of the rod R may at the time be placed. In the drawings the hand-lever N is in the lowest notch of the quadrant O, acting upon and causing the wheels L and M to support the plows E, F, and G clear of the ground. By placing the hand-lever N at the center notch of the quadrant O, the wheels L' and M would assume the position shown by dotted lines. By the arrangement for the adjustment of the wheels L' and M, the depth of the furrows can be easily regulated.

We claim as our invention—

1. The frame of a gang-plow, composed of the rails A, B, and J and brace K, in combination with the clevis-block T and the plow-standard E, F, and G, having shoulders and flat shanks, as shown and described.
2. The bell-crank P, having holes *p* pierced in one of its arms, as shown, and connected to the cranked axle L by the rod R and lever S, in combination with the rod Q, quadrant O, hand-lever N, and cranked axle M, arranged and operated substantially as and for the purpose specified.

THOMAS RICHARDSON.
MALCOLM MCINNES.
